ZACHARY E. RUSSELL, OF SAUK RAPIDS, MINNESOTA, ASSIGNOR TO CHRISTINE M. WARREN, GUARDIAN OF THE ESTATE OF CLYDE W. WARREN, DOING BUSINESS AS THE WARREN SHADE CO., OF SAUK RAPIDS, MINNESOTA

CORD HOLDING MECHANISM FOR SHADES

Application filed June 17, 1929. Serial No. 371,472.

This invention relates to a curtain or shade and particularly to a device for holding the cords by which such a shade is rolled up or manipulated. It is desirable to have a cord-holding mechanism which is simple in construction and which can be easily and quickly operated.

It is an object of this invention, therefore, to provide a holding means for a shade which clamps the manipulating cords of the shade and which is quite simple and can be easily and quickly operated.

It is a further object of the invention to provide such a curtain holder or cord clamping mechanism comprising a member over which a pair of cords move having a lever pivoted adjacent thereto with a clamping portion adapted to be swung in one direction to move said clamping portion toward said member to clamp the cords and to be swung in the opposite direction to move said clamping portion away from said member to release said cord.

It is more specifically an object of the invention to provide a curtain holder or cord clamping mechanism comprising a pulley over which the cords move, a lever pivoted adjacent the pulley having an eccentric portion adapted to move toward the pulley to clamp the cords when the lever is swung in one direction and to move away from said pulley to release the cords when said lever is swung in the opposite direction, said lever having an arm with perforated means thereon through which the cords pass whereby said lever can be swung by means of said cords.

These and other objects and advantages of the invention will be fully set forth in the following description made in connection with the accompanying drawing, in which like reference characters refer to similar parts throughout the several views, and in which:

Fig. 1 is a view in front elevation of a portion of a curtain showing the invention applied thereto;

Fig. 2 is a top plan view of Fig. 1;

Fig. 3 is a vertical section taken on line 3—3 of Fig. 1 as indicated by the arrows, and

Fig. 4 is a partial view similar to Fig. 1,

shown on an enlarged scale, a certain portion thereof being broken away and other parts being shown in vertical section.

Referring to the drawing, a shade of the slat type is shown comprising the slats 10 secured together by spaced cords or warp 11, said curtain being supported in any suitable manner from a bar 12 as by having the top slat 10a secured thereto. As shown in Fig. 3, the top slat 10a is secured between a slat or bar 10b and another slat 10c, all of which are secured to the rear of bar 12.

The curtain is adapted to be rolled up and for this purpose a pair of cords 13 are provided which extend around the curtain and have one end thereof fastened to brackets 14 by having the same pass through an aperture 14a of said brackets and secured by a knot 13a. Said cords also pass upward at one side of the curtain and run over pulleys 15 carried in one side of brackets 14, said brackets having a U shaped portion 14b enclosing said pulleys 15 and supporting the trunnion pins thereof. Brackets 14 are shown as secured to the top of bar 12 by the screws 16. After passing over the pulleys 15, cords 13 pass respectively over pulleys 17 mounted on brackets 14 and between the same and plates 18 secured to the brackets 14 by rivet pins 19.

A bracket 20 is provided having holes therein for receiving the securing screws 21 by which said bracket is secured to the front of bar 12 at one end thereof. A headed stud 22 is riveted in bracket 20 on which is journaled a pulley 23 having flanges at each edge thereof at its periphery so as to form a groove having a comparatively flat bottom. A pair of pins 24 are riveted into bracket 20 and project therefrom at either side of pulley 23 adjacent the top of the pulley, said pins being disposed in close proximity to the periphery of said pulley. Cords 13 pass laterally from pulleys 17 beneath one pin 24 and over pulley 23, the same being disposed in the groove of said pulley, said cords then extending downwardly from said pulleys. A lever 25 is fulcrumed on a pivot stud 26 similar to stud 22 and also riveted into bracket 20. Washers 27 are disposed at either side of lever 25 on stud 26. Lever 25 has a portion 25a adjacent its

pivot having its lower edge or surface 25 formed eccentrically to said pivot and provided with corrugations. Said surface 25b is arranged so that it moves toward pulley 23 5 and the corrugations thereof engage cords 13 when lever 25 is swung in one direction and moves away from said pulley when said lever is swung in the opposite direction. Lever 25 has an arm 25c extending downwardly at one 10 side of pulley 23, said arm having a laterally extending portion 25d provided with a pair of holes 25e through which cords 13 respectively pass.

In operation, the curtain will be manipulated by the cords 13 which extend downwardly at the side of the curtain to a point conveniently in reach of the operator. When the curtain is to be rolled up, the cords 13 will be grasped and swung outwardly to the 20 right as shown in dotted lines in Fig. 1. This swinging motion swings the edge 25b away from the pulley and the cords are released. The cords can then be pulled upon to roll up the curtain or allowed to pass upward as the 25 curtain unrolls. When the curtain has been brought to the desired point, the operator will again swing the cords downwardly toward the left, as seen in Fig. 1 and lever 25 will be moved, as the cords pass therethrough 30 at its lower end, and surface 25b will be brought into clamping engagement with the cords 13 clamping the same against the pulley 23. The cords 13 will be clamped so that they cannot move and the curtain will be held in 35 the desired position. It will be noted that when the lever 25 is in clamping position the holes 25e are substantially in vertical alignment with the edge or periphery of pulley 23. There is no tendency therefore for the 40 gravity action of the lever or cords to move the same from clamping position. The cords are guided to and held in proper position on the pulley by the pins 24 which prevent the cord moving off of the pulley when not clamped. The left-hand pin 24 of Fig. 1 also insures that the cords will engage the pulley 45 for quite a distance and always be in proper position to be clamped.

From the above description it is seen that 50 applicant has provided a very simple and efficient curtain handling device and holding means. The clamping means and operating lever are all on one part and cooperate with a simple pulley. The device can be easily 55 and inexpensively made and is at the same time quite rugged and durable. The device has been amply demonstrated in actual practice and found to be very successful and efficient and is being commercially made.

50 It will, of course, be understood that various changes may be made in the form, details, proportions and arrangement of the parts, without departing from the scope of applicant's invention, which, generally stated, consists in a device capable of carrying out the

objects above set forth, in the novel parts and combinations of parts disclosed and defined in the appended claim.

What is claimed is:—

The combination with a rollable shade and a supporting member upon which the shade is supported, of a bracket secured to said supporting member at one end of the same, a pulley mounted on said bracket for rotation about a horizontal axis, a pair of pulleys 75 mounted on said member in spaced relation, a pair of cords secured respectively to said member at spaced points, projecting downwardly and around the shade then upwardly and over said last mentioned pulleys, both of said cords extending substantially horizontally at one side of said first mentioned pulley and over the top of said pulley and then extending substantially vertically downwardly at the other side of said first mentioned 80 pulley, a lever pivoted for swinging movement on a horizontal axis over said first mentioned pulley and having a single jaw extending downwardly over the top of said first mentioned pulley and adapted to clamp said cords against said first mentioned pulley, said lever having a downwardly projecting arm extending substantially vertically and at the last mentioned side of said first mentioned pulley, said arm having apertures in its lower 85 end through which the vertically extending portions of said cords project, whereby the vertically extending portions of said cords may be swung substantially horizontally to positively swing said lever and clamp and release said jaw from both of said cords simultaneously.

In testimony whereof I affix my signature.
ZACHARY E. RUSSELL.
